Patented Feb. 27, 1968

210,300

TOY GYROSCOPE TOP

Duane W. Miller, 246 Westfield St.,
Rochester, N.Y. 14619

Filed Dec. 9, 1966, Ser. No. 4,979

Term of patent 3½ years

(Cl. D34—15)

FIG. 2

FIG. 1

FIG. 3

FIG. 1 is a side elevational view of a toy gyroscope top, showing my new design;

FIG. 2 is a plan of one end thereof; and

FIG. 3 is a plan of the opposite end thereof.

The side not shown in FIG. 1 is substantially identical with the side shown.

I claim:

The ornamental design for a toy gyroscope top, substantially as shown and described.
